CLAIM

The ornamental design for a sport bottom wear, as shown and described.

DESCRIPTION

FIG. 1 is a top, front, and left perspective view of a sport bottom wear in accordance with the present design;

FIG. 2 is a front elevational view thereof;

FIG. 3 is a rear elevational view thereof;

FIG. 4 is a left side elevational view thereof;

FIG. 5 is a right side elevational view thereof;

FIG. 6 is a top plan view thereof;

FIG. 7 is a bottom plan view thereof; and,

FIG. 8 is a top, front, and left perspective view of the sport bottom wear shown in an alternate configuration wherein a portion of the front of the sport bottom wear protrudes when balls are held therein.

The broken lines showing balls in the front portion of the sport bottom wear illustrate environmental structure. The broken lines shown in the interior edge of the pouch illustrate stitching. The remaining broken lines illustrate portions of the sport bottom wear. None of the broken lines form part of the claimed design.
